CLAIM

The ornamental design for a combined cushion and frame module for patient interface, as shown and described.

DESCRIPTION

FIG. 1 is a front perspective view of a combined cushion and frame module for patient interface showing a first embodiment of our new design;

FIG. 2 is an enlarged front perspective view of the combined cushion and frame module of FIG. 1, in isolation;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is reverse perspective view thereof;

FIG. 10 is a front perspective view of a combined cushion and frame module for patient interface showing a second embodiment of our new design;

FIG. 11 is an enlarged front perspective view of the combined cushion and frame module of FIG. 10, in isolation;

FIG. 12 is a front view thereof;

FIG. 13 is a rear view thereof;

FIG. 14 is a top view thereof;

FIG. 15 is a bottom view thereof;

FIG. 16 is a left side view thereof;

FIG. 17 is a right side view thereof; and,

FIG. 18 is reverse perspective view thereof.

The broken lines in the drawings depict portions of the combined cushion and frame module for patient interface that form no part of the claimed design.
